UNITED STATES PATENT OFFICE.

EDWARD J. SCHROEDER, OF SUMMIT, NEW JERSEY.

DECK-LAMP LIGHTING FIXTURE.

Application filed March 8, 1923. Serial No. 623,575.

To all whom it may concern:

Be it known that I, EDWARD J. SCHROEDER, a citizen of the United States, residing at 281 Summit Avenue, Summit, in the county 5 of Union and State of New Jersey, have invented certain new and useful Improvements in Deck-Lamp Lighting Fixtures, of which the following is a specification.

This invention relates to a deck lamp 10 lighting fixture, and the novelty consists in the adaptation and arrangement of the parts, as hereinafter fully pointed out.

There are various types of lighting fixtures having shade holders which are adapted 15 to hold the lighter form of shades in a secure manner, and in such a way that they will not be readily broken. But there is a large demand for a fixture embodying a shade holder adapted to hold a larger and 20 heavier type of shade in a secure manner, and also in a way which will not cause breakage under unusual conditions prevailing on steamships and railroad trains.

Such a device must also permit the easy 25 and quick removal and replacement of the shade for cleaning or replacement in case of breakage. My device meets all of these requirements, furnishing a shade holder which firmly and securely grips a shade of a heavy 30 type if desired and permitting the easy and quick removal of the shade for cleaning and restoring to position in the fixture again. My device also is adapted to facilitate the 35 operator in the removal of the shade by the operative releasing means pulling downward, which is the natural direction for the operator reaching up to ceiling fixtures of this type.

Referring to the drawings; Figure 1 is a 40 vertical section of my device showing the electrical connecting means; Figure 2 is a side elevation of the spider; Figure 3 is a top plan view of Fig. 2. Figure 4 is a top plan view of the finger clamping device; 45 and Figure 5 is a side elevation of the same.

In the drawings 10 is a spider adapted 50 to be rigidly secured to the ceiling where the fixture is to be used by means of suitable screws 11 which pass through the bor- 55 ings 19 in the spider 10, and said spider 10 has a dental internally threaded boring 12 adapted to receive an externally threaded 60 socket support member 13, to which is mounted at its lower end in the usual man- 65 ner a socket 14 of usual construction. A locking nut 20 threaded over the upper ex-

ternal threading of said socket support member 13 is adapted to be screwed against the spider 10 after the socket support 13 has been screwed into position in said spider 60 10, in order to lock said socket support member 13 into position and support the same against horizontal pressure. Electrical wires 15 are adapted to pass through the spider 10 and the socket support 13 and be 65 connected with the socket 14 in the usual well known manner.

A canopy 16 is adapted to be rigidly secured to the spider 10 by means of suitable screws 17 engaging internally threaded boring 18 of the spider 10. The canopy 16 has at its lower edge an outturned flare 21, which has a beveled face 22 on the inside thereof, and there are slots or openings 23 through the sides of said canopy 16. A thickened 75 portion 24 on the inside of said canopy 16 terminates at its upper portion in a cylindrical flange 25 having an external threading 26, over which a cylindrical connector member 27 is adapted to be threaded. The 80 connector member 27 has an internal threading 28 around the inside of the upper edge thereof, and a cylindrical member 29 having an external flange 30 at its lower edge and around which is mounted a spiral 85 spring 31 has an external threading 32 at its upper edge adapted to engage the internal threading 28 of the connector 27. A cylindrical sliding member 33 having an in- 90 turned cylindrical flange 34 around its upper edge is adapted to be mounted between the cylindrical member 29 and the canopy 16 so that the flange 34 will rest on the upper 95 part of the upper end of the spiral spring 31 so as to be under the constant upward 95 spring tension of the spring 31, which at its lower end rests on the flange 30 of the cylindrical member 29. Internally threaded collar members 35 are adapted to be screwed 100 into the sliding cylindrical member 33 at 36 so that said collar members 35 register in the slots 23 of the canopy 16. An annular ring 37 is adapted to be mounted around the canopy 16 by means of screws 38 which are adapted to thread into the internal 105 threading of the collars 35, thereby rigidly securing the annular ring 37 to the sliding cylindrical member 33. A cylindrical finger clamping member 39 having holes 40 there- 110 in is adapted to be rigidly secured by means of screws 41 through said holes 40 to the base of the sliding cylindrical member 33.

The spring clamping member 39 has individual finger members 42, the lower portions of said fingers 42 forming reverse curves so as to be adapted to grip the upper outturned flange 43 of a shade 44.

In assembling my fixture the spider 10 will be first rigidly secured to the ceiling by means of screws 11, and the connecting wires 15 will then be run through the socket support 13 which will be rigidly screwed into position in the internal boring 12; and the locking nut 20 threaded onto the upper end of the socket support 13 will then be turned up tightly in position against the spider 10. The socket 14 will then be connected to the wires 15 in the usual manner and rigidly secured in position to the lower end of the socket support 13 in the well known manner. The connector member 27 will then be screwed in position over the threaded portion 26 of the cylindrical flange 25 of the thickened portion 24 of the canopy 16. The spiral spring 31 will then be placed in position around the cylindrical member 29 so as to rest on the external flange 30 of the same, and the cylindrical sliding member 33 will be slid over the upper end of said cylindrical member 29 and the spring 31 so that the inturned flange 34 of the sliding member 33 will rest on the upper end of the spiral spring 31, and these two cylindrical members 29 and 33 with the spring 31 between them will then be mounted within the canopy 16 by screwing the cylindrical member 29 by means of the external threading 32 into the internal threading 28 of the connector member 27. The collar members 35 can then be screwed in position into the cylindrical member 33 at 36 through the openings 23 in the canopy 16, and the annular ring 37 can then be rigidly secured to the sliding member 33 by means of screws 38 adapted to be screwed into the collar members 35. The cylindrical finger clamping member 39 can then be rigidly secured to the base of the sliding member 33 by means of screws 41. The canopy 16 together with the assembled parts therein can then be rigidly secured to the spider 10 by means of screws 17.

In operating my device the operator need only pull down on the annular ring 37, thereby compressing the spring 31 and releasing the cylindrical finger clamping member 39 from its normal tension against the beveled face 22 of the out-turned flare 21 of the canopy 16, whereupon the fingers 42 of the cylindrical finger clamping member 39 are released so that the globe 44 may be slipped into position or removed therefrom quickly and easily without the danger of cracking or breaking the same.

It will be understood that an electric light bulb of usual construction is adapted to be

mounted in the socket 14 for purposes of illumination.

Many variations may be made in my device without departing from the spirit and intent of the invention.

I claim:

1. In a lighting fixture a spider adapted to be rigidly secured to the ceiling, a canopy rigidly secured to said spider, spring clamping fingers mounted in said canopy under constant spring tension upwardly against the lower part of said canopy, and means on the outside of said canopy for releasing said spring clamping members and a socket support rigidly secured to said spider within said canopy.

2. In a lighting fixture a spider adapted to be rigidly secured to the ceiling, a canopy rigidly secured to said spider, a threaded flange on the upper interior portion of said canopy, a connecting element screwed over said flange, a central cylinder having exterior threading at its upper end adapted to screw into an interior threading on said connecting element at its upper end, a sliding cylinder mounted between said central cylinder and said canopy by means of a spiral spring around said central cylinder which is supported on a flange around the lower edge of said central cylinder and supports said sliding cylinder by an inturned flange at its upper edge, a spring clamping finger member rigidly secured to said sliding cylinder at its lower edge, an annular ring around said canopy connected through openings in said canopy to said sliding cylinder and a socket support rigidly secured to said spider within said canopy.

3. In a lighting fixture a spider adapted to be rigidly secured to the ceiling, a canopy rigidly secured to said spider, spring clamping means mounted in said canopy under constant spring tension against said canopy, comprising a slideable cylinder mounted under upward spring tension between an inner cylinder and said canopy, and means for releasing said spring clamping members and a socket support rigidly secured within said canopy.

4. In a lighting fixture a spider adapted to be rigidly secured to the ceiling, a canopy rigidly secured to said spider, spring clamping means mounted in said canopy under constant spring tension against said canopy, comprising a slideable cylinder mounted under upward spring tension between an inner cylinder and said canopy, and means for releasing said spring clamping members comprising an annular ring rigidly secured through openings in said canopy to said slideable cylinder, and a socket support rigidly secured within said canopy.

In testimony whereof I affix my signature.
EDWARD J. SCHROEDER.
